UNITED STATES PATENT OFFICE.

EMIL PETERS AND ANDREW LAMBERT, OF CHICAGO, ILLINOIS.

LEGGING.

1,347,657.

Specification of Letters Patent. Patented July 27, 1920.

Application filed March 13, 1918. Serial No. 222,236.

To all whom it may concern:

Be it known that we, EMIL PETERS and ANDREW LAMBERT, citizens of the United States, residing at Chicago, in the county of Cook and State of Illinois, have jointly invented certain new and useful Improvements in Leggings, of which the following is a specification.

This invention relates to improvements in leggings and one object is to provide a legging formed with an integral nose which is formed of a flexible material adapted to conform to the shape of the shoe of the wearer and which nose is provided with shape-retaining means so that its efficiency as a protection against inclement weather is not impaired by wear or rough usage. A further object is to provide a legging having a water proof surface or skin, and a legging which is neat and dressy in appearance and that, at the same time, is cheap to manufacture.

With the foregoing and other objects in view the invention consists in the combination and arrangement of parts to be hereinafter fully described, pointed out in the appended claim and illustrated in the accompanying drawing which forms a part of this specification and in which—

Figure 1 is a view in side elevation of one embodiment of our invention.

Fig. 2 is a front view of Fig. 1.

Fig. 3 is a cross section, enlarged, on line 3—3 of Fig. 1.

Fig. 4 is a longitudinal sectional view, enlarged, on line 4—4 of Fig. 2.

Like reference characters denote corresponding parts throughout the several views.

The body portion 1 of the legging is shaped to approximately fit the calf and ankle of the wearer and it is formed of an inner fabric of leather 2, or like material, and an outer fabric of water proof material 3 such as rubber. One edge of the legging is covered by the binding strip 5 and the other with a similar strip 6, the edges overlapping each other. The inner and outer layers of material 2, 3 are suitably secured together and are also connected by the eyelets 7 through which the lacing cord 8 passes

to releasably secure the overlapped edges together in a well known manner.

A curved pointed nose is formed at the lower extremity of the legging and embedded in the same is the stiff anchor-shaped spring 10, the wings of the anchor extending along the tapering edges of the nose 9 and the anchor stem extending through the bridge 11 of the nose. The spring 10 will stiffen the nose 9 and cause the same to retain its shape during the life of the legging and will cause the nose to snugly conform to the shape of the shoe of the wearer. A strap 12 carried by the legging is adapted to pass beneath the instep of the wearer to hold the legging in proper position. The legging being laced shut along the side presents a neat and dressy front and a front devoid of openings or crevices through which snow or wind may penetrate to the discomfiture of the wearer.

What is claimed is:—

In a legging, a body portion comprising an inner fabric and an outer fabric, the latter being a substantially water proof material, the edges of said body portion being overlapped and adapted for sliding adjustment upon each other or for close binding engagement with each other, flexible means criss-crossing said overlapped edges upon both sides of the same for effecting the desired adjustment thereof, binding strips for the overlapped edges of said body portion, a flexible nose terminating said body portion, flexible anchor-shaped stiffening means embedded in said nose, the wings of said anchor-shaped means extending along the sides of said nose and the stem of said means extending along the bridge of said nose, and a strap secured to and depending from said body portion.

In testimony that we claim the foregoing as our own we hereto affix our signatures in the presence of two subscribing witnesses.

EMIL PETERS.
ANDREW LAMBERT.
